UNITED STATES PATENT OFFICE

ALBERT C. FISCHER, OF KANSAS CITY, MISSOURI.

SHINGLE OR BLOCK CONSTRUCTION.

REISSUED

Application filed April 20, 1918. Serial No. 229,681.

To all whom it may concern:

Be it known that I, ALBERT C. FISCHER, a citizen of the United States, residing at Kansas City, in the county of Jackson and 5 State of Missouri, have invented certain new and useful Improvements in Shingle or Block Constructions; and I do declare the following to be a full, clear, and exact description of the invention, such as will enable others skilled in the art to which it appertains to make and use the same, reference being had to the accompanying drawings, and to the letters and figures of reference marked thereon, which form a part of 10 this specification.

My invention relates to shingle and block construction and more particularly to shingles or blocks for roof or floor coverings; the principal object of the invention 20 being to provide shingles or blocks wherein a backing portion, provided either as an integral part, or as a separate piece applied thereto, extends beyond the edges of the shingle or block body so that it may underlie the edges of a juxtaposed shingle or block to effect a closed joint and prevent leakage 25 therebetween.

It is also an object of the invention to provide shingles or blocks of this character 30 wherein the backing extends from one or more edges thereof and wherein such extended edges are provided with a mastic coating, such as asphalt, tar, or the like whereby overlapped portions may be sealed 35 and bonded together to make a weather proof and serviceable roof.

In accomplishing these objects I have provided improved details of structure the preferred forms of which are illustrated in the 40 accompanying drawings, wherein:—

Fig. I is a perspective view of a preferred form of shingle constructed according to the present invention.

Fig. II is a perspective view of a portion 45 of a roof covered with shingles constructed and applied according to the present invention.

Fig. III is a cross-sectional view, on the line III—III Fig. II, illustrating the laying 50 of the shingles and the over-lapped relation of the backing edges.

Fig. IV is a detail perspective view of shingles of a slightly modified form wherein the backing extends only at one side of the 55 shingle body.

Fig. V is a perspective view of a part of

a roof, illustrating the preferred method of applying the shingles of the type shown in Fig. IV.

Fig. VI is a cross sectional view on the line VI—VI, Fig. V.

Fig. VII illustrates another form of shingle wherein the backing member is of the same size as the shingle, but is offset at one side and end thereof.

Fig. VIII is a perspective view illustrating the preferred method of assembling the shingles shown in Fig. VII, to cover a roof.

Fig. IX is a sectional view on the line IX—IX, Fig. VIII.

Fig. X is a detail perspective view of another form of shingle wherein the backing member extends at all sides of the shingle body.

Fig. XI is a perspective view illustrating the assembly upon a roof of shingles having the construction shown in Figure X.

Referring more in detail to the drawings:

In Fig. I, I have shown the preferred form of shingle. This shingle comprises a 80 body portion 1 which may be of composition felt and asphalt construction of any desirable thickness and is here shown as having a gravel coating to insure a durable wearing surface.

The body 1 is provided with a backing strip 2, preferably a heavy strip of tarred paper, felt or similar substance, which is applied to or formed as a part of the body so that the opposite edges 3—3' thereof extend substantially beyond the side edges of the shingle body.

The backing 2, the same as the shingle bodies, may be made in different thicknesses and may be applied by sticking the same to 95 the shingle body after the latter has been formed or may be made as a part of the body, and is preferably a flexible and pliable material, and while it is not always necessary, in most instances the upper surfaces 100 of the exposed margins of the backing strips are coated with a layer 5 of asphalt, tar or similar substance so that when the shingles are laid on a roof, as is presently described, the coating will serve to stick or seal the 105 overlapped edges together to close the joint between the shingles.

When laying these shingles to cover a roof, the lower course is placed first, with the bodies 1 of the shingles spaced apart and 110 leaving drainage channels 8 between them, which may be alined if desired to provide

continuous channels through the whole incline of the roof. The protruding margins 3, 3' of the backing strips, at opposite sides of each shingle, extend, respectively, over 5 and beneath the protruded margins of the backing strips of adjacent shingles at opposite sides thereof, and thus not only form water-tight joints but also provide the bottoms of the drainage channels. The over- 10 lying backing strip for instance, strip 3 in each instance is extended slightly beneath the body 1 of the adjacent shingle, that is to say, between said body and its backing strip, whereby the free edges of said over- 15 lying backing strips are interlocked against curling up of the strip or opening of the seam. The mastic coating serves to make the strips adhere together, and so seals the joints that leakage therebetween is prevented. 20

Small nails or tacks may be driven through the upper edges of the shingles as shown at 6 to anchor the same to the roof or else small cleats as shown at 7 may be 25 applied to their free end or side margins which more effectively hold the same in place.

The following courses are then laid to slightly overlap the upper edge of the shingles of the first courses and preferably as 30 shown in Fig. II, with the spaces between the shingles of each course in alignment, as this forms a serviceable and the most attractive roof, although a very serviceable roof 35 is provided when the shingles are laid in broken joints.

Fig. IV shows a slight modification from the preferred form of shingle in that the base or backing extends only at one side of 40 the shingle body. Shingles of this construction are laid, as shown in Fig. V, a little closer together than those first described and may be laid in either straight or broken joint courses. The extended or marginal 45 portions of the backing of these shingles may also be coated with a mastic substance and when laid are extended beneath the edge of the adjacent shingle sufficiently that an effective sealed joint is made. Shingles of 50 this construction are also laid in courses and are over-lapped as shown in Fig. V and may be fixed to the roof either with tacks, cleats or in any other desirable manner.

The form of shingle illustrated in Figs. 55 VII, VIII and IX is still another modification of that shown in Fig. I. In this type the backing member is cut the same size as the shingle body and is then applied thereto so that its margins —a— and —b— extend 60 at one side and at the lower end of the shingle body, and when the shingles are laid to cover a roof, as shown in Fig. VIII, they are placed with their body portion tightly together without over-lapping one another, but 65 with marginal portions of the backing mem-

bers overlapping one another and underlying adjacent body portions, and preferably in straight, vertical and broken horizontal joints.

It will be noted that in this construction 70 and method of laying the shingles all vertical joints between shingle bodies are entirely closed by the underlying backing strip margins *a* and the horizontal joints are closed by the underlying backing margins *b*, 75 and said margins *a* and *b*, and also the edges of the shingle bodies when coated with a mastic substance, will bond the shingles together to form practically a single sheet of roofing and will absolutely seal all the joints 80 against leakage.

The shingle shown in Fig. X differs from the others only in that the backing strip 2 has margins *a*—*b*—*c* and *d* extending at all margins of the shingle body. Shingles 85 of this construction are laid, as shown in Fig. XI, close together with the joints either broken or in alignment, and the margins of the backing at opposite edges of the bodies extended respectively beneath and above the 90 margins of the backing members of adjacent shingles, the upper margins in each instance being extended between the shingle bodies and their backing strips. Various means, such as tacks, cleats, etc, may be used 95 to hold the shingles in place.

It is apparent that shingles or blocks of the present character should be made at a reasonable cost and when properly applied would form a serviceable and durable roof. 100

It is also apparent that by coating the edges of the backing strip with the mastic material, when the edges are placed in overlapped relation the mastic will join the parts together and seal the joint to positively prevent weather leakage therethrough. 105

While I have shown the preferred methods of laying the shingles it is apparent that various other designs could be used without departing from the spirit of the 110 invention.

It is also noted that while I have described the shingles as being of composition construction with a flexible backing, which is preferred because the flexibility of the backing adapts it to be pressed out of its own plane in developing a smooth upper surface on the body portion which overlaps the margins of the backing members, yet some of the advantages of the present invention, as 120 for instance, introducing the margin of one backing member between the body and backing member of an adjacent shingle, would still be present even if the shingles be made of slate, tile or other non-flexible material 125 and still be applied in the same manner, and I therefore do not wish to be limited to any particular material of construction.

I claim—

1. A roof comprising shingles, each of 130

- which comprises a body portion having a flexible backing portion extending from opposite side edges thereof, said shingles being arranged with one of the extending portions of certain of said shingles lying between the body portion and the backing of an adjacent shingle.
2. In a roof, flexible shingles comprising body portions each having flexible backing portions extending from opposite edges thereof, with the extended backing portions of adjacent shingles overlapping, and one of them extending beneath the adjacent body portion.
- 10 3. A shingle comprising a body portion having a backing member extended at an edge or edges thereof and separable from the body portion near the edge or edges of the latter.
- 15 4. A roof comprising shingles each of which comprises a body portion having a flexible backing portion extending from a side edge thereof, said shingles being arranged with the extending portions of certain of said shingles underlying and adhering to portions of adjacent shingles.
- 20 5. A roof comprising shingles each of which comprises a body portion having a flexible backing portion extending from a side edge thereof, said shingles being arranged with the extending portions of certain of said shingles lying between the body portion and the backing of an adjacent shingle.
- 25 6. A shingle comprising a body portion having a flexible backing extending from an edge thereof said backing portion being separable from said body portion near an edge of said body portion.
7. A shingle, or the like, comprising a rectangular body portion of substantial thickness, and a backing portion affixed to the body portion, presenting free marginal portions extending at a side and end thereof, and separable from the body portion near the edge of the latter.
8. In a roof or the like, the combination of shingles in courses, said shingles comprising body portions having backing members applied thereto in position to leave flexible marginal portions extending beyond the edges of the body portions, said portions having mastic coating applied thereto; said shingles being assembled with their body portions in substantially the same plane, with their flexible marginal portions lapped one over another, and with each outer marginal portion extending in between the underlying marginal portion and the body which carries it.
9. In a shingle roof, shingles comprising body portions of substantial thickness and backing members of flexible material providing flexible marginal projections thereon; said shingles being assembled with their body portions in substantially the same plane, with their edges in the direction of drainage spaced apart to develop drainage channels between them, and with their marginal portions overlapped in position to provide bottoms to said drainage channels.

In testimony whereof I affix my signature.

ALBERT C. FISCHER.
